UNITED STATES PATENT OFFICE

154,444

DESIGN FOR A CABINET FOR BEVERAGE
VENDING MACHINE

John Vassos, Norwalk, Conn., assignor to Mills
Industries, Incorporated, Chicago, Ill., a corporation of Illinois

Application July 3, 1947, Serial No. 140,083

Term of patent 14 years

(Cl. D52—3)

To all whom it may concern:

Be it known that I, John Vassos, a citizen of the United States of America, residing at Norwalk, in the county of Fairfield and State of Connecticut, have invented a new, original, and ornamental Design for a Cabinet For Beverage Vending Machine, of which the following is a specification, reference being made to the accompanying drawing, forming a part thereof.

The single figure of the drawing is a perspective view of a cabinet for beverage vending machine, showing my new design. The side of the cabinet not disclosed is the same as the side shown, and the back and top are plain and unornamented.

I claim:

The ornamental design for a cabinet for beverage vending machine, as shown and described.
JOHN VASSOS.
